SALVE CONTAINER

Mathew Goldine, Chicago, Ill.

Application October 13, 1934, Serial No. 748,163

2 Claims. (CL 221—60)

This invention relates to improvements in containers and more particularly to a container for salves and like products. One object is to provide a container of this type that is substantially the shape of a lead pencil, means being provided for sealing the ends of the container.

A further object is to provide a multi-walled container of uniform diameter throughout except for one flattened end, the container being collapsible so that the contents may be ejected through one end completely, or part at a time, as may be desired and when but a part of the contents are evacuated the container serving to hold the remainder as satisfactorily as though partial evacuation had not been accomplished, and to evacuate this remainder or part thereof as desired.

A further object is to provide a container for a medicated composition and which container will at all times protect the composition from moisture and extraneous matter generally and provide means for applying the composition to the body when and as desired.

A further object is to provide a salve container of novel appearance that may be readily carried upon the person without inconvenience and a container that is inexpensive to manufacture and sanitary in use.

With the foregoing and other objects in view the invention consists in the combination and arrangement of parts to be hereinafter fully described, pointed out in the claims and illustrated in the accompanying drawing which forms a part of this application for patent and in which—

Fig. 1 is a view of the container in side elevation.

Fig. 2 is a view similar to Fig. 1 but rotated to a position at right angles thereto.

Fig. 3 is an enlarged fragmentary sectional view taken on the line 3—3 of Fig. 2.

Fig. 4 is a cross sectional view through Fig. 3 on the line 4—4.

Fig. 5 is a side view of Fig. 3 with a part of one wall broken away.

Fig. 6 is an end view of Fig. 1.

Fig. 7 is a view in perspective of the straw portion of the container.

Like reference characters denote corresponding parts throughout the several views.

The container includes a straw as a main body portion, a wrapping of lead foil being applied to the straw body, a paper label being wrapped about the lead foil, and a wrapping of cellophane applied to the label. The straw, an ordinary

soda water straw, may be chemically treated to make it grease proof by applying a coating of nitro-cellulose compound such as a solution of gun cotton to the inner wall of the straw. The straw is now filled with the salve, one end of the straw being pinched or flattened during the process. The lead foil is now wrapped about the straw, the label then wrapped about the lead foil, and the cellophane wrapped about the label.

The lead foil is preferably extended somewhat beyond the flattened end of the straw and the cellophane extended materially beyond the lead foil. The tip end of the lead foil and the projecting portion of the cellophane are now folded back upon the flattened end of the container and upon the immediately adjacent round portion thereof, the extreme and flattened end of the container now being crimped or pressed together as by a pair of pliers or pincers so that the folded cellophane and lead foil will retain its shape and position. At the opposite non-flattened end of the container the lead foil and cellophane are folded over the open end of the straw to form a closure therefor to retain the contents therein.

The reference numeral 1 denotes the straw about which the lead foil 2 is wrapped, the straw being filled with the compound 3 while one end of the straw is pressed together by the fingers or support in which it may be disposed. The label 4 is now applied to the lead foil and the cellophane 5 applied to the label, the lead foil extending slightly beyond the ends of the straw and the cellophane extending materially beyond the crimped end thereof. The cellophane is now folded back to form the flap 6, which is gently pressed down against the flattened and rounded container portions and the lead foil and cellophane pressed inwardly to form a closure for the end 7 of the container.

To evacuate the contents of the container the lead foil and cellophane are opened away from the end 7 and the flattened end of the tube manually squeezed to force out the compound.

What is claimed is:—

1. A container and dispenser for salve-like compounds comprising a tube of flexible material crimped at one end, a wrapping of lead foil about said tube and extending beyond both ends thereof, a label about said lead foil, and a sheet of cellophane wrapped about said label and tube and extending materially beyond one end thereof and beyond the end of said lead foil, said lead foil and cellophane being folded back upon the flattened end of the container.

2. A container and dispenser for salve-like compounds comprising a straw crimped at one end, a wrapping of lead foil about said straw and extending beyond the ends thereof, said lead foil extending more beyond the crimped end thereof than beyond the opposite end, a paper label about said lead foil, and a sheet of cellophane wrapped about said label and about the ends of said lead foil and extending mate-

rially beyond the latter at the flattened end of the straw, said cellophane being folded upon itself and down upon said lead foil at the flattened end of the straw, said lead foil and cellophane being folded inwardly over the non-flattened end of the straw, and a coating of nitro-cellulose compound upon the inner wall of said straw.

MATHEW GOLDINE.
